CONVERTIBLE LADDERS

Conrad A. Osovski and Raymond H. Shaver, Newark Valley, N.Y., assignors to Chesebro Whitman Manufacturing Corporation, Newark Valley, N.Y., a corporation of New York

Filed May 26, 1958, Ser. No. 737,629

8 Claims. (Cl. 182—26)

The present invention relates to ladders in general, and more particularly to a multi-purpose device which may be utilized as a step ladder either on horizontal or uneven ground, and may be converted into an extension ladder.

An important object of the invention is to provide a ladder which is of simple construction, easy to manipulate, and safe in operation either as an extension or as a step ladder.

Another object of the invention is to provide a device of the above character which may be assembled by utilizing component parts of known construction.

An additional object of the invention is to provide a multi-purpose ladder of the above described character which, in addition to being capable of use as an extension or step ladder, may be further adjusted for use as a step ladder on uneven or stepped ground.

A further object of the instant invention is to provide a ladder of the above described character which consists of a relatively small number of component parts, and which may be collapsed into a relatively small and compact package for transport and storage.

A concomitant object of the invention is to provide a multi-purpose ladder one part of which is longitudinally adjustable when used as a step ladder, and which is of adjustable overall length when used as an extension ladder.

The above and other objects of the invention are attained by the provision of a ladder comprising two relatively movable parts so connected with each other that one thereof is slidable with respect to the other in upward and downward directions; of means for locking the two parts in a selected position when they are inclined with respect to each other; and means for locking the parts to each other when the parts are in substantially parallel planes but displaced with respect to each other.

Other features, advantages and attributes of the novel ladder will become apparent and will be pointed out in greater detail in the course of the following detailed description of certain embodiments selected for illustration in the accompanying drawings, in which:

Fig. 1 is side elevational view of the improved ladder, showing in full lines relative positions of the stationary front part and of the movable back support on a horizontal floor, and in phantom lines the position of back support when the ladder is used on stairs;

Fig. 2 is rear elevational view of the structure as seen from the right-hand side of Fig. 1;

Fig. 3 is an enlarged detail view of the locking device against downward movements of the back support as seen from line 3—3 of Fig. 1;

Fig. 4 is an enlarged section taken on line 4—4 of Fig. 2, as seen in the direction of arrows, showing one of the locking means in retaining position to prevent upward displacement of the back support;

Fig. 5 illustrates in section the upper end of stationary front part with the spring lock of Fig. 4 in the position it

assumes when acted upon by a rung of the upwardly advancing movable part or back support;

Fig. 6 illustrates the novel article in side elevation when used as an extension ladder;

Fig. 7 is an enlarged front elevational view of the converted extension ladder shown in Fig. 6;

Fig. 8 is an enlarged detail view of a portion of the back support, and of the upper end of front part, as seen from line 8—8 of Fig. 7 in the direction of arrows;

Fig. 9 is an enlarged detail view of a spring lock with certain parts broken away; and

Fig. 10 is perspective view of a modified locking and retaining means against downward displacements of the movable part which can replace the bails of the type shown in Fig. 3.

Referring now in greater detail to the drawings, and first to Figs. 1 and 2, the improved convertible ladder 20 therein shown comprises a stationary front part or ladder 21 and a movable part or back support 22. The front

part comprises a pair of rails 23, 24 which are connected by means of steps 25 so mounted as to have their major surfaces in substantially horizontal planes when the ladder 20 is in the position of Fig. 1. A certain amount of hardware, such as tie rods 26, nails 27 driven

into each end face of steps 25, and washers 28, as well as stops or blocks 29 inserted between each tie rod and the underside of the adjacent step, is shown in these figures but has been omitted in other illustrations because the construction of front part 21 or back support 22 by

itself is well known and forms no part of the present invention. It will also be noted that the lower end faces of front rails 23, 24, as well as the lower end faces of rear rails 30, 31, are provided with customary antiskid attachments, preferably rubber feet 32, 33, respectively.

The back support, in addition to rails 30, 31, comprises a number of preferably uniformly spaced connecting rungs 34. The step ladder shown in Figs. 1 and 2 is one of medium height having five steps 25 and six rungs 34, but it will be readily understood as this description pro-

ceeds that the length of parts 21, 22, i.e. the actual size of the multi-purpose ladder 20, has no bearing on the invention which is equally applicable to relatively short, medium-length, or relatively long step ladders.

Front part 21 carries two releasable locking assemblies

45 35a, 35b, respectively, whose purpose is to prevent upward movements of back support 22 when the article is used as a step ladder, while the other locking assembly 36a, 36b prevents descent of the back support when the novel device is used as an extension ladder. In addition,

40 back support 22 is slidably connected with the front part 21 by means of a guide device 37 which leads the back support during its displacements with respect to the front part and prevents excessive spreading of device 20 when used as a step ladder.

55 Each of the first mentioned locking means 35a, 35b comprises a hook-shaped member 38 defining therein a recess 39 for the reception of a rung 34 when the device is used as a step ladder on horizontal, uneven, or stepped ground (see Fig. 1). Members 38 of respective locks

60 35a, 35b are pivotally connected to front rails 23, 24 and are preferably resiliently urged into the position of Fig. 4 by means of a spring or the like, as will be described in greater detail in connection with Fig. 9.

Each of locking means 36a, 36b for preventing descent

65 of back support 22 with respect to the front part 21 comprises a hook or bail 40, one of which is shown greatly enlarged in Fig. 3. The bails are pivotally connected to the inner surfaces of front rails 23, 24, respectively, at a suitable distance from guide means 37, each bail defin-

70 ing an upwardly facing cavity or recess 40a when in the position of Figs. 1 to 4 and 6 to 8. These bails become

active when the novel device 20 is used as an extension ladder as shown in Figs. 6 to 8. During lifting of back-support 22 with respect to the front part 21 in the direction of arrow X, bails 40 are pivoted into the position of Fig. 5. The bails are integrally formed with abutment or stop plates 41, the latter having flanges 42 traversed by rivets 43 which connect the locking means 36a, 36b to the respective front rails 23, 24. The position of rivets 43 is so selected that the undersides of plates 41 bear against the upper face of adjacent step 25 when the locking means 36a, 36b are in the position of Figs. 1 to 4 and 6 to 8. This can be observed in Fig. 4.

Guide means 37 comprises a U-shaped metallic member of flat stock having a base 44 and two legs 45, 46 with the latter rigidly connected to respective rails 23, 24 by means of rivets 47 adjacent to the upper end of front part 21. It will be noted in Figs. 4 and 5 that the base 44 is so inclined as to offer full surface support to the adjacent end faces of rear rails 30, 31 when the novel device is used as a step ladder, that is, when the back support 22 is inclined with respect to front part 21.

The ladder is further provided with customary collapsible side arms or spreaders 48, 49 which, however, cannot be rigidly connected with the back support 22 since the latter should not be permanently fixed to front part 21 but must be slideable with respect thereto, when necessary. Therefore, each spreader has one of its ends pivotally connected to one of front rails 23, 24, its other end being pivotally fixed to one of cuffs 50, 51 which are so shaped as to permit sliding movements of rear rails 30, 31, respectively. Cuffs 50, 51 are connected to legs 45, 46 of the guide means 37 by straps 52, 53, respectively, which latter maintain the cuffs at a constant distance from base 44.

When the ladder 20 is in the position shown in full lines in Fig. 1, its front part 21 and back support 22 are prevented from movements with respect to each other

(a) By hooks 38 of respective locking assemblies 35a, 35b whose recesses 39 receive the uppermost rung 34 of the back support and thus prevent the latter's upward displacements with respect to the front part 21;

(b) By spreaders 48, 49 over cuffs 50, 51; and

(c) By end faces 23a, 24a of front rails 23, 24 which, together with spreaders 48, 49, prevent angular displacements of the back support. Inclined end faces 23a, 24a bear against the longitudinal end faces 30a, 31a of the back support's rails, and the other end faces 30b, 31b of the latter bear against the inner faces of cuffs 50, 51. Some stresses may be taken up by the base 44 of guide means 37.

When the back support is to be moved into its phantom-line position 22' whereby its legs 33 rest upon the stair 54, hooks 38 are pivoted away from the engaged rung 34 to permit upward displacements of the back support to the extent sufficient to move its legs into positions 33' in which they rest upon the stair 54. Hooks 38 thereupon engage the second rung 34. During such displacement, rear rails slide in cuffs 50, 51 and in guide means 37, their surfaces 30a, 31a moving along the end faces 23a, 24a, of the front rails.

When the novel device 20 is to be used as an extension ladder, bails 40 of locking assemblies 36a, 36b are first moved into the positions corresponding to that of bail 40 shown in Fig. 5, and the spreaders 48, 49 are collapsed. Hooks 38 of upper locking assemblies 35a, 35b are thereupon disconnected from the adjacent rung 34 and the back support is free to slide with respect to front part 21 in the direction of arrow X. When the ladder is extended to a desired length, bails 40 are returned into positions assumed by the bail shown in Fig. 4, and the back support is caused to descend a small distance in downward direction until the adjacent rung 34 enters into the recesses 40a in said bails. The ladder is thus brought into the position of Figs. 6 and 7 in which the bails not only take up the weight of back support 22 but also prevent the latter's pivotal movements

about the meeting edges of surfaces 23a, 23b and 24a, 24b of respective front rails 23, 24. It will be seen that the bails 40 not only perform a supporting but also an anti-pivoting function; therefore, their recesses 40a must be deep enough to prevent movement of a rung 34 therefrom even if the ladder is subjected to considerable pivoting stresses in directions tending to move the lower ends of rear rails 30, 31 away from the front rails. A modified one-piece locking and retaining device against downward displacements of back support 22 is illustrated in Fig. 10 and will be described in greater detail hereinafter.

As before stated, each locking device 35a, 35b in its preferred form comprises a spring biased hook 38 constantly tending to move into the position of Fig. 4 in which its recess 39 receives a rung 34. To that end, shank 55 of the hook 38 is pivotally connected to one of front rails 23, 24 by means of a bolt 56 (see Fig. 9), the bolt also passing through a mounting plate 57 and a cover plate 58 whose side walls 59, 60 are bent into planes 20 at right angles to its main plane and are fixed to mounting plate 57. One leg of leaf spring 61 bears against the shank 55 of hook 38 while its other leg abuts against the side wall 59 and thus constantly urges hook 38 in the direction of arrow Y. The spring 61 forms a loop 25 about a rivet 62 which connects the cover plate 58 to mounting plate 57. The latter has a number of apertures 57a for the passage of bolts or rivets connecting it to one of the front rails.

Shank 55 of each hook 38 carries a cam plate 63, best shown in Figs. 4 and 5, connected thereto by a pivot pin 64. Cam plate 63 has an arcuate end face 65 and a lip or flange 66 substantially at right angles to its main body portion. The lip 66 is adjacent to the lower end 38a of the hook 38 and abuts thereagainst when a rung 34 strikes against the end face 65 of the cam plate. Thus, as the back support advances in the direction of arrow X (see Fig. 5), its rungs 34 consecutively abut against the end faces 65 of cam plates 63 compelling the latter to pivot about members 64 and to thus cause their lips 66 to strike against the hooks' terminals 38a. The hooks thereupon pivot about members 56 in the direction of arrow Z against the force of resilient members 61 to the extent necessary to permit passage of a rung 34 past the cam plates 63. Hooks 38 thus perform a series of oscillating movements, the number of oscillations depending upon the extent of upward displacement of the back support, i.e. upon the number of rungs 34 consecutively abutting against the cam plates.

To return ladder 20 from the position of Figs. 6 and 7 into that of Figs. 1 and 2, back support 22 is lifted 50 beyond its position of Fig. 7 enabling the bails 40 of locking means 36a, 36b to be pivoted into the position of Fig. 5. The back support is thereupon free to descend and the downwardly advancing rungs 34 ride over the arcuate end faces 38b of hooks 38 causing the latter to swing in the direction of arrow Z to permit descent of the back support. Cam plates 63 offer no resistance to such movement because of their pivotal connection to shanks 55. Resilient members 61 return the hooks into position of Fig. 4 immediately after surfaces 38b are 55 out of contact with a rung 34.

When the front part 21 and back support 22 are again in the approximate positions of Figs. 1 and 2, cam plates 63 are pivoted either by hand or by suitable manipulation of back support 22 to cause entry of a selected rung 34 into the recesses 39 of hooks 38. Spreaders 48, 49 are 60 then expanded and the article 20 may again be utilized as a step ladder.

Fig. 10 shows a unitary bail type hook 67 which can 65 replace the locking means 36a, 36b. Instead of abutting against the step 25 in the manner of plates 41 forming part of locking means 36a, 36b, the assembly 67 is formed with a pair of prongs 68, 69 which abut against the end surfaces 23b, 24b of respective front rails 23, 24. The portion of locking and retaining device 67 intermediate 70 rails 23, 24 defines a pair of abutments 70, 71 against

downward displacements of the movable back support 22, and a portion of inverted U-shape consisting of sections 72, 73 and 74 to prevent pivoting movements of the back support. Portions 75, 76 are pivotally held in brackets 77, 78 fixed to respective front rails 23, 24.

The advantage of locking and retaining device 67 is in that it is made of a single piece and thus requires a single step for pivoting it out of retaining position or back into retaining position. It may be pivoted into idle position by the upwardly advancing rung 34 of back support 22 when the operator desires to convert the device back into a step ladder. The distance between front rails 23, 24 at the point of connection of device 67 being greater than the distance between parallel rails 30, 31 of back support 22, a rung 34 of the latter merely engages the portions 70, 71 to pivot the locking device 67 into idle position. The pivoting movement of abutments 68, 69 is unimpeded.

It will be observed that the back support 22 need not carry any hardware, as all locking, retaining, and guide means are carried by the front part 21. This is desirable because any known type of simple ladder having parallel rails spaced by rungs or other connecting means may be combined with the front part to form a step- or extension ladder therewith. Moreover, while it is preferred to utilize rungs of circular cross-sectional contour, the use of such rungs is not absolutely necessary, since the locking means 35a, 35b and 36a, 36b may be modified in such a way as to accommodate rungs or steps of different configuration.

Members 57, 58, 61, 62 and 63 may be omitted and each hook 38 merely connected to the front rail by its bolt 56. Of course, in such simplified construction, the hooks must be manipulated by hand to be moved into positions out of path of the rungs 34 at least when the latter advance in upward direction.

If the step ladder consists of two identical parts similar to front part 21, the locking and guide means are connected to one of the parts, the other part being moved with respect thereto in the previously described manner.

Such and many other modifications will readily occur to persons skilled in the art, and are therefore considered to be within the nature of the present invention as defined in the appended claims.

What we claim and desire to protect by Letters Patent is:

1. A convertible ladder comprising, in combination, a first part having a pair of spaced rails each having a first end and a second end; a second part comprising two parallel rails and a plurality of spaced connecting elements therebetween; guide means attached to the first part adjacent to the first ends of said first mentioned rails for so leading the rails of said second part that the latter is free to perform sliding movements in its own plane toward the first and the second ends of said first mentioned rails and limited pivotal movements between a position of parallelism with the first part and inclination with respect to said first part; two collapsible spreaders each pivotally fixed to one rail of said first part; a substantially tubular element connected to each spreader and each slidably receiving one rail of said second part; a pair of straps each connecting one of said tubular elements with said guide means; and locking means fixed to the first part intermediate said guide means and the second ends of said first mentioned rails for releasably engaging a selected connecting element and for holding the second part against sliding movements toward the second ends of said first mentioned rails and against pivotal movements from the position of parallelism with respect to said first part when said spreaders are collapsed.

2. A convertible ladder comprising, in combination, a first part including two rails each having a first end, a second end and an inclined surface adjacent to the first end, and a plurality of steps between said rails; a second part having two parallel rails and a plurality of connect-

ing elements therebetween; guide means consisting of a bracket fixed to the rails of said first part of the proximity of said first ends thereof; a pair of substantially cuff-shaped elements each articulately attached to said bracket and each slidably receiving one rail of said second part in such a way that the second part is free to perform sliding movements in its own plane and said bracket permitting pivotal movements of said parts with respect to each other between a first position in which the second part is substantially parallel with the first part and a second position in which the rails of the second part abut against the inclined surfaces of the first mentioned rails; first locking means comprising at least one hook-shaped member pivotally fixed to the first part adjacent to the first ends of the first mentioned rails for releasably engaging a connecting element against sliding movements of the second part in a direction toward and past the inclined surfaces of said first mentioned rails; and second locking means comprising at least one hook-shaped member connected to the first part intermediate said bracket and the second ends of said first mentioned rails for releasably holding a selected connecting element against sliding movements of the second part in a direction toward the second ends of said first mentioned rails and against pivoting movements from a position in which the second part is substantially parallel with the first part, whereby the ladder may be utilized as a step ladder when a connecting element is engaged by said first mentioned locking means and the second part is inclined with respect to the first part, and as an extension ladder when the second part is displaced with respect to the first part in a plane parallel thereto and said second locking means engages the adjacent connecting element.

3. A multi-purpose ladder comprising, in combination, a front part including a pair of rails each having a first end and a second end, and a plurality of steps for interconnecting said rails; a back support having two parallel rails and a plurality of rungs for so spacing said rails that their distance corresponds to the distance between the first ends of the first mentioned rails; a substantially U-shaped bracket having a pair of legs each fixed to one of the first mentioned rails in the proximity of said first ends thereof, and a base spaced from the front part and embracing the back support; a pair of extendable and collapsible spreading members each having a first end pivotally fixed to one of said first mentioned rails at a point spaced from the legs of said bracket intermediate said bracket and the second ends of said first mentioned rails, and a second end; a pair of substantially cuff-shaped elements each connected to the second end of one of said spreading members each articulately connected to and spaced from said bracket, and each slidably receiving one rail of said back support whereby the latter is free to perform sliding movements in its own plane and pivotal movements with respect to the front part between a first position in which the spreading members are expanded, and a second position in which the spreading members are collapsed and the back support is parallel with and adjacent to the front part; first locking means comprising a pair of hook-shaped members each pivotally connected to one of said first mentioned rails adjacent to the first ends thereof for releasably engaging a selected rung and for holding the back support against sliding movements in its own plane in a direction toward and past the first ends of said first mentioned rails; and second locking means comprising at least one hook-shaped member fixed to at least one of said first mentioned rails intermediate said second end thereof and said bracket for releasably engaging a selected rung when said spreading members are collapsed and said back support is adjacent and parallel to the front part in such a way that the back support is held against sliding movements in its own plane in a direction toward the second ends of the first mentioned rails, and against pivoting movements with respect to the front part.

4. A convertible ladder comprising, in combination, a first part including two rails each having a first end, a second end and an inclined surface adjacent to the first end, and a plurality of steps for so connecting the rails that their distance decreases toward the first ends thereof; a second part having two parallel rails and a plurality of rungs so spacing the rails that their distance corresponds to that between the inclined surfaces of said first mentioned rails; a U-shaped bracket fixed to the rails of said front part and embracing the back support; two expandable and collapsible spreaders each having a first end pivotally connected to one rail of said front part and a second end; a substantially tubular element connected to the second end of each spreader and each slidably receiving one rail of the back support, each tubular element being spaced from and pivotally connected to said bracket whereby the back support is free to perform pivotal movements between a first position in which its rails abut against the inclined surfaces of said first mentioned rails when said spreaders are expanded, and a second position in which the back support is adjacent to and parallel with the front part when said spreaders are collapsed; a pair of spring biased hook-shaped locking members each fixed to one of said first mentioned rails adjacent to the latter's first end, said locking members being permanently urged into a position in which they engage a selected rung to prevent sliding movements of the rails of said back support in a direction toward the inclined surfaces of said first mentioned rails, and being movable into a second position away from the rungs when the back support slides with respect to said front part; and at least one hook-shaped locking member pivotally fixed to the front part intermediate the second ends of its rails and said bracket for releasably engaging a selected rung when the spreaders are collapsed and the back support is adjacent to and parallel with the front part in such a way that the back support is held against sliding movements toward the second ends of said first mentioned rails and against pivotal movements with respect to said front part.

5. A convertible ladder comprising, in combination, a first part having a pair of rails each having an end, and spaced steps therebetween; a second part having a pair of parallel rails and a plurality of connecting elements therebetween; guide means connected with the front part adjacent to the ends of said first mentioned rails; a pair of substantially tubular elements each slidably receiving one rail of the second part for movements of the latter in its own plane and each connected to said guide means; a pair of spreading means each connected with one rail of the first part and with one of said tubular elements, each of said spreading means having a first position in which the rails of said second part are adjacent to the

rails of said first part, and a second position in which the second part is inclined with respect to the first part; first locking means connected to the first part adjacent to the ends of said first mentioned rails and comprising at least one hook-shaped member pivotally fixed to said first part in the path of the connecting elements when the second part is inclined with respect to the first part and its rails slide in said tubular elements in a direction toward the ends of said first mentioned rails, said first locking means being adapted to engage a selected connecting element and to hold the second part against sliding movements in said direction whereby said ladder may be utilized as a step ladder when the spreading means is in said second position; and second locking means comprising at least one hook-shaped member fixed to said first part at a point distant from the first locking means for engaging a selected connecting element and for holding the second part against movements in a direction opposed to said first mentioned direction when the spreading means is in said first position, and for maintaining the spreader means in said first position, whereby the ladder may be utilized as an extension ladder.

6. The combination according to claim 5, wherein said second locking means comprises a pair of hook-shaped members each pivotally fixed to one of said first mentioned rails and each comprising a portion so mounted as to abut against the adjacent step of said first part when the members are in one extreme position for engaging a connecting element.

7. The combination according to claim 5, wherein said second locking means comprises a single hook-shaped member extending substantially between and pivotally fixed to said first mentioned rails for rotation about an axis parallel with said steps, said member having at least one portion abutting against one of said first mentioned rails when the member is in the position for engaging a selected connecting element.

8. The combination according to claim 5, wherein each of said first mentioned rails has a surface at said end thereof of such inclination as to be in contact with the rails of said second part when the spreading means is in said second position.
